(57) **CLAIM**

The ornamental design for an arm sleeve, as shown and described.

DESCRIPTION

FIG. 1 is a front view of an arm sleeve showing my new design, wherein the arm sleeve is illustrated being worn by a person;

FIG. 2 is a side view of the arm sleeve shown in FIG. 1;
FIG. 3 is a rear view of the arm sleeve shown in FIG. 1;
FIG. 4 is a front elevational view of the arm sleeve shown in FIG. 1, wherein the arm sleeve is lying flat and the torso strap has been removed for clarity of disclosure;

FIG. 5 is a rear elevational view of the arm sleeve shown in FIG. 4;

FIG. 6 is a right side elevational view of the arm sleeve shown in FIG. 4;

FIG. 7 is a left side elevational view of the arm sleeve shown in FIG. 4;

FIG. 8 is a top plan view of the arm sleeve shown in FIG. 4;

FIG. 9 is a bottom plan view of the arm sleeve shown in FIG. 4;

FIG. 10 is a top plan view of the torso strap shown in FIGS. 1 and 3;

FIG. 11 is a bottom plan view of the torso strap shown in FIG. 10; and,

FIG. 12 is a side view of the torso strap shown in FIG. 10. The partial human figure illustrated by dash-dot-dash broken lines assists to illustrate the arm sleeve in a position of use and forms no part of the claimed design.

The torso strap illustrated as broken lines with longer segments in FIGS. 1, 3, and 10-12 forms no part of the claimed design. The torso strap is shown with a symbolic break in its length. The appearance of any portion of the torso strap between the break lines forms no part of the claimed design.

The dash-dot-dash broken lines shown in FIGS. 4 and 5 represent portions of the arm sleeve that form no part of the claimed design.

The broken lines with shorter segments represent portions of the arm sleeve that form no part of the claimed design.
